DESIGN FOR AN EXHAUST PIPE EXTENSION

Linus E. Russell, Springfield, Ohio

Application August 28, 1936, Serial No. 64,617

Term of patent 7 years

To all whom it may concern:

Be it known that I, Linus E. Russell, a citizen of the United States, residing at Springfield, Clark County, Ohio, have invented a new, original, and ornamental Design for an Exhaust Pipe Extension, of which the following is a specification, reference being had to the accompanying drawing, forming a part thereof, in which

Fig. 1 is a perspective view of an exhaust pipe extension embodying the new design.

Fig. 2 is a top plan view thereof.

Fig. 3 is a fragmentary side elevation thereof.

Fig. 4 is a rear end elevation thereof.

The design comprises an extension for an exhaust pipe of a motor vehicle or the like having its top surface longitudinally fluted and terminating in a spoon-like enlargement.

I claim:

The ornamental design for an exhaust pipe extension substantially as shown and described.

LINUS E. RUSSELL.
